(57) **CLAIM**

The ornamental design for a tire and wheel rim assembly for automobile, as shown and described.

DESCRIPTION

FIG. 1 is a left side elevational view of a tire and wheel rim assembly for automobile, showing my new design;

FIG. 2 is a front elevational view thereof;

FIG. 3 is a top plan view thereof;

FIG. 4 is a left side elevational view thereof, showing the tire removed from the wheel rim for clarity of disclosure;

FIG. 5 is a cross-sectional view thereof, taken along line V—V of FIG. 4;

FIG. 6 is an enlarged fragmentary view thereof, taken along line VI—VI of FIG. 5; and,

FIG. 7 is a further enlarged fragmentary cross-sectional view of the tire and wheel rim assembly for automobile, taken along line VII—VII of FIG. 1.

The broken line depictions of a portion of a wheel, the tire tread area and inner bead area are indicative of environmental structure and form no part of the claimed design.
